KNITTING MACHINE

Vincent Lombardi, Garden City, N. Y., assignor
to Lombardi Knitting Machine Co. Inc., New
York, N. Y., a corporation of New York

Original application February 26, 1935, Serial No.
8,256. Divided and this application Septem-
ber 27, 1935, Serial No. 42,368

11 Claims. (Cl. 66—36)

This invention relates to knitting machines; the present application being a division of my co-pending application, Serial No. 8,256, which was filed February 26, 1935, as a continuation in part of my co-pending application, Serial No. 5 720,921, filed April 17, 1934.

Among the objects of the invention are the provision of a knitting machine of an improved character embodying a unitary member which 10 comprises both a knitting element portion and a selective element portion.

Another object is the provision in a knitting machine of means which will maintain such a unitary element or a similar element in a set 15 position at certain times but which will permit free movement thereof at other times.

Other objects of the invention will in part be obvious and will in part appear hereinafter.

The invention accordingly comprises the features of construction, combination of elements, and arrangement of parts, which will be exemplified in the constructions hereinafter set forth and the scope of the application of which will be indicated in the claims.

For a fuller understanding of the nature and 25 objects of the invention reference should be had to the following detailed description taken in connection with the accompanying drawing, in which:

Figure 1 is a vertical sectional view of a portion of a knitting machine embodying the invention and showing a knitting element in the form of a needle;

Fig. 2 is a similar view illustrating a modification;

Fig. 3 is an enlarged section on the line 3—3 of Fig. 2;

Fig. 4 is a section on the line 4—4 of Fig. 3;

Fig. 5 is a fragmentary view similar to Fig. 2 showing a modified arrangement;

Fig. 6 is an enlarged section on the line 6—6 of Fig. 5;

Fig. 7 is a view similar to Fig. 1 showing another modification;

Fig. 8 is a section on the lines 8—8 of Fig. 7;

Fig. 9 is a view of a modified form of needle; and

Fig. 10 shows another modified form of needle.

While a considerable number of means for producing complicated patterns by effectuating movements of knitting elements between a multiplicity of positions have been devised in the past, these usually involve mechanisms which are extremely complicated and/or involve the use of arrangements wherein fragile elements

are so placed that they are extremely likely to be broken in operation. In spite of the fact that the pattern machines in commonest use have for many years utilized pattern wheels or other rotating pattern elements to separate knitting elements and other elements into two positions for subsequent operations, the use of such rotating elements for multiple positioning, so far as is known, has not occurred to the art even though there has been very considerable activity over 10 a number of years in the development of mechanisms for the production of complicated fabrics.

In my co-pending application Serial No. 720,- 15 921 above referred to, there are disclosed knitting machines embodying selective elements individual to each of a series of knitting elements mounted for sliding movement on a bed and arranged to be selectively set in a multiplicity of different positions and to be selectively actuated in accordance with the settings thereof. The 20 present invention is primarily directed to constructions wherein the knitting element and the selective element are part of a unitary knitting member, and are not independent elements either attached or unattached. However, in certain of 25 its aspects it is adapted to be embodied in other constructions, including attached but independent, knitting and selective elements wherein similar problems are present.

The knitting-element portion may be a latch 30 needle portion, a beard needle portion, or a yarn manipulating element of other desired type; the various members utilized may be of any of the types illustrated in my said co-pending application, Serial No. 720,921, or of other suitable 35 type as will be apparent to those skilled in the art; the knitting bed may be stationary or movable, and may be of any desired form or shape; and other modifications of a wide variety of types may be made.

In Fig. 1 there is shown a needle bed 15, which may be of the cylindrical type, and which is formed with slots 16 about its periphery. In these slots is a series of needles 17 which in the present instance are of the latch type and which are held 45 in the slots by an annular spring 18. The lower portions 19 of the needles are arranged for swinging on an axis adjacent to the spring 18 to permit the same to be set in a multiplicity of positions lateral of the slots. Each needle is formed with 50 transverse bends 20 and 21 whereby the selective portions 19 will be frictionally retained in the positions in which they are set. There is provided also actuator mechanism which revolves about the cylinder when the same is stationary, or which 55

may be stationary if the cylinder rotates. This mechanism includes an aligning cam 22, a pattern wheel 23, and an advancing cam 24, which in the present instance act in sequence. Each needle 5 is formed with a plurality of shoulders, as indicated at 25 and 26, which are designed to engage the cam 24 when the portion 19 is in an outward or an intermediate position respectively, but not when it is in an inward position. As will be noted, 10 these shoulders slope outwardly, and the upper surface of the cam 24 slopes in a similar direction, so as to prevent inward movement of the portion 19 when the shoulders are engaged by the cam. The pattern wheel is formed to provide a multiplicity of setting configurations, which in the 15 present instance comprise slots 27, certain of which are empty, certain of which contain short actuators 28, and others of which contain long actuators 29, in the manner illustrated more in detail in Fig. 8. The pattern wheel is formed with a gear 30 meshing with teeth 31 on the bed 15, so as to be rotated during the relative movement of the bed and the actuator mechanism.

In operation, all of the portions 19 are moved 25 outwardly by the cam 22 bearing against an inward projection 32 on the needle, and certain of the needles are thereupon pushed part way in by the short actuators on the pattern wheel, and others are pushed in all the way by the long 30 actuators on the pattern wheel. Thereafter, the cam 24 advances to the upper line at the top of Fig. 1 those needles which were passed by the pattern wheel; advances to the middle line at the top of the figure those needles which were 35 operated by the short actuators so that the same will be in a position for tucking, interlocking or the like design operations; and passes those needles which were operated upon by the long actuators so that these needles will not receive 40 yarn from a yarn carrier forming a part of the actuator mechanism.

In many knitting operations it is highly desirable that no strain be put on the yarn, and to this end it is often important that the needles move 45 easily so that they will yield to such a pull as the fabric exerts. With the foregoing and other considerations in view the invention contemplates the provision of means which will hold the selective portion of a unitary needle or other knitting element in an outwardly set position, but which 50 will not resist longitudinal movement of the needle. One form of construction embodying such means is shown in Figs. 2-4. In these figures the parts are generally similar to the parts shown in Fig. 1 and are designated by similar reference numerals with the addition of the subscript *a*. The slots 16*a* are narrowed at their outer portion 55 as indicated at 33 just above the plane of action of cam 22*a* so as to bear frictionally against a part 34 of the sleeve portion 19*a* of the needle when the latter is in an outward or an intermediate position, but not when it is in an inward position. Accordingly, the portion 19*a* will be frictionally 60 retained in an outward position until the cam 24*a* has engaged either the shoulder 25*a* or 26*a*, but will not be frictionally retarded in its movement after it has been restored or has restored itself to its normal inward position. In the present instance, the extension 32 is omitted and the cam 22*a* acts directly on the thin lower end 35 of the needle 17*a*; an outwardly extending slot portion 36 being provided.

A similar arrangement is shown in Figs. 5 and 6 wherein there are shown similar parts designated by similar reference numerals, except that 75 they are followed by the subscript *b*. In this

arrangement there are provided springs 37 which extend inwardly from a member 31' toward the portions 34*b* on the needles so that when these portions are moved outwardly the springs will bear against them to frictionally retain them in 5 position to be engaged by the cam.

As will be apparent, constructions such as illustrated in Figs. 2-4 and 5-6 may be employed to hold in an outward position a selective element which is independent of but attached to a knitting 10 element in instances where frictional attaching means such as disclosed in my co-pending application Serial No. 680,168 are not utilized, and may be employed in instances where the selective element is movable only to one position besides its 15 normal one.

In instances such as those wherein the use of a cam 22 is undesirable, wherein the use of frictional retaining means of any sort is not desired, or wherein a normally outward needle is to be 20 used, there may be utilized an arrangement such as shown in Figs. 7 and 8 wherein the needles are at all times held in an outwardly swung position except when they are being acted upon by the pattern wheel or when they are engaged by or 25 inside of the cam. The cam, in this instance, is disposed beneath the pattern wheel so that it will engage the needles while the pattern wheel is acting thereon. In these figures the general construction is similar to that of Figs. 1 and 2, the 30 parts being indicated by similar reference numerals with the subscript *c*. Each needle 17*c* is held in an outward position at all times by a spring 38 except when an actuator on the pattern wheel 23*c* is in engagement therewith. The cam 24*c* is 35 directly below the pattern wheel so that it will engage the shoulder 26*c* when the pattern wheel has no actuator in its slot. When the pattern wheel has a short shoulder 28*c* in a slot the needle will be pushed part way in and the shoulder 25*c* 40 engaged by the cam. When the pattern wheel has a long actuator 29*c* in its slot the needle will be pressed all the way in so that both shoulders will ride to the rear of the cam. After the cam has once engaged a particular shoulder it will 45 continue such engagement until the positioning of the needle is completed. It will thus be seen that no setting cam is required nor is any frictional retaining means necessary. Fig. 7 also illustrates how the gear 30*c* of the pattern wheel may mesh 50 with projections 31*c* on the needles, if desired.

It will be apparent that the needles or other knitting elements, though unitary, need not be integral. In Fig. 9 there is illustrated a needle comprising an upper independent portion 39 having a bent end 40 fitting within a slot 41 in a lower portion 42. Except for this feature the body of the needle is the same as that shown in Fig. 1 and is operated in the same way. In order to exemplify a beard needle, however, the needle 55 is shown with a beard 43 rather than with a latch. In Fig. 10 there is shown a needle similar to that shown in Fig. 7, except that its lower portion 43' is removably connected with its upper portion 44 by means of a bend 45 on the latter and a slot 46 in the former, and except that the portions 44-45 are continued downwardly to 60 form a spring 47 which serves the same purpose as the spring 38 of Fig. 7.

Since certain changes may be made in the 70 above construction and different embodiments of the invention could be made without departing from the scope thereof, it is intended that all matter contained in the above description or shown in the accompanying drawing shall be 75

interpreted as illustrative and not in a limiting sense.

I claim:

1. A knitting machine comprising a needle bed, a series of slots arranged along said bed, a unitary element swingably mounted in each slot and having a knitting element portion and a portion formed with a plurality of cam-engaging surfaces, actuator mechanism, said actuator mechanism and said bed being mounted for relative movement, cam means forming a part of said actuator mechanism and adapted to selectively engage said cam-engaging surfaces and to selectively act on the various unitary elements in accordance with the setting thereof to cause them to be in various ones of a multiplicity of positions longitudinally of said slots, and a rotatable element also forming a part of said actuator mechanism adapted to act selectively upon the unitary elements and providing about its periphery a series of configurations of a multiplicity of types for effectuating a selective setting of said unitary elements in a multiplicity of different lateral positions upon their axes of swinging movement.
2. A knitting machine comprising a needle bed, a series of slots arranged along said bed, a unitary element swingably mounted in each slot and having a knitting element portion, actuator mechanism, said actuator mechanism and said bed being mounted for relative movement, means forming a part of said actuator mechanism and adapted selectively to act on the various unitary elements in accordance with the setting thereof to cause them to be in various ones of a multiplicity of positions longitudinally of said slots, outwardly acting means to position said elements in outward position in said slots, and a rotatable element forming part of said actuator mechanism and arranged to receive about its periphery a given number of actuator members at evenly-spaced positions and a plurality of actuator members protruding in one manner disposed at certain of said positions and a plurality of actuator members protruding in another manner disposed at other of said positions, no actuator members being provided at still other of said positions, the positioning of said rotatable elements and said actuator members being such that the actuator members protruding in different manners will press the unitary elements inwardly to different extents so that a selective setting of said unitary elements in a multiplicity of different lateral positions upon their axes of swinging movement will be effected.
3. A knitting machine comprising a bed, a series of unitary knitting members arranged along said bed, actuator mechanism, said actuator mechanism and said bed being mounted for relative movement, said knitting members being mounted for longitudinal sliding movement and for movement of portions thereof between a multiplicity of lateral positions, cam means forming a part of said actuator mechanism and adapted to selectively impart longitudinal movement to said knitting members in accordance with which of said lateral positions they are in, means selectively to set said knitting member portions in various ones of said lateral positions for selective action by said cam means, and frictional means acting to maintain said knitting members in certain of said lateral positions but not to resist movement of the knitting members when in at least one of said lateral positions.
4. A knitting machine comprising a bed, a series of slots in said bed, unitary knitting mem-
- bers mounted for sliding movement in said slots, actuator mechanism, said actuator mechanism and said bed being mounted for relative movement, said knitting members having portions movable between a multiplicity of lateral positions in said slots, and cam means forming a part of said actuator mechanism and adapted to selectively impart sliding movement to said knitting members in accordance with which of said lateral positions they are in, said slots being narrowed in a lateral portion thereof to maintain said portions in one of said lateral positions when moved thereto but not to resist movement of the knitting element in any normal position.
5. A knitting machine comprising a bed, a series of unitary knitting members arranged along said bed, actuator mechanism, said actuator mechanism and said bed being mounted for relative movement, said knitting members being mounted for longitudinal sliding movement and for movement of portions thereof between a multiplicity of lateral positions, cam means forming a part of said actuator mechanism and adapted to selectively impart longitudinal movement to said knitting members in accordance with which of said lateral positions they are in, means selectively to set said knitting member positions in various ones of said lateral positions for selective action by said cam means, and frictional means comprising laterally extending leaf springs acting to maintain said knitting members in certain of said lateral positions but not to resist movement of the knitting members when in at least one of said lateral positions.
6. A knitting machine comprising a series of slots, knitting members in said slots and capable of movement between a plurality of positions lateral of said slots, and means to frictionally maintain a knitting member in at least one of said positions when moved thereto for action thereon by a selecting member but not to resist movement of the knitting member under other of the conditions occurring during the operation.
7. A knitting machine comprising a series of slots, knitting members in said slots and capable of movement between a plurality of positions lateral of said slots, and means comprising a narrow slot portion to maintain a knitting member in at least one of said positions when moved thereto for action thereon by a selecting member but not to resist movement of the knitting member under other of the conditions occurring during the operation.
8. A knitting machine comprising a series of slots, knitting members in said slots and capable of movement between a plurality of positions lateral of said slots, and resilient frictional means to maintain a knitting member in at least one of said positions when moved thereto for action thereon by a selecting member but not to resist movement of the needle under other of the conditions occurring during the operation.
9. A knitting machine comprising a bed, a series of unitary knitting members arranged along said bed, actuator mechanism, said actuator mechanism and said bed being mounted for relative movement, said knitting members being mounted for longitudinal sliding movement and for movement of a portion thereof between a multiplicity of lateral positions, cam means forming a part of said actuator mechanism and adapted to selectively impart longitudinal movement to said knitting members in accordance with which of said lateral positions they are in, re-

- silient means for normally maintaining said portion in one of said lateral positions, and means to selectively move said portions to various other of said lateral positions, said members being adapted to be engaged by said cam means when in certain of said other of said lateral positions.
10. A knitting machine comprising a needle bed, a series of slots arranged along said bed, unitary elements swingably mounted in said slots and having knitting element portions, actuator mechanism, said actuator mechanism and said bed being mounted for relative movement, means forming a part of said actuator mechanism and adapted selectively to act on the various unitary elements in accordance with the setting thereof to cause them to be in various ones of a multiplicity of positions longitudinally of said slots, and a rotatable element also forming a part of said actuator mechanism and providing on its periphery a series of configurations of a multiplicity of types for effectuating a selective setting of said unitary elements in a multiplicity of different lateral positions upon their axes of swing-

ing movement, said selectively acting means having a single cam surface and each of said unitary elements being formed to provide longitudinally spaced cam-engaging surfaces, each adapted when said element is in a particular one 5 of said lateral positions to be intercepted by said single cam surface for causing the unitary elements to be in said various ones of said multiplicity of longitudinal positions after the operation of said single cam surface, the axis of swinging 10 movement being beyond said cam-engaging surfaces in the direction of movement of the elements by said cam surface.

11. A knitting machine comprising a series of slots, knitting members in said slots and capable 15 of movement between a plurality of positions lateral of said slots, and means to frictionally resist movement of a knitting member when moved to at least one of said lateral positions for action thereon by a selecting member but not to resist 20 movement of the knitting member when in at least one of said lateral positions.

VINCENT LOMBARDI.
